(57) **CLAIM**

The ornamental design for a clock, as shown and described.

DESCRIPTION

FIG. 1 is a perspective view of the clock of the present invention.

FIG. 2 is a front elevation of the clock.

FIG. 3 is a rear elevation of the clock.

FIG. 4 is a top plan view of the clock.

FIG. 5 is a side elevation taken from the left side of the clock as viewed in FIG. 2.

FIG. 6 is a side elevation of the clock taken from the opposite side to that of FIG. 5; and,

FIG. 7 is a bottom plan view of the clock.

The broken line showings throughout the views are for illustrative purposes only and form no part of the claimed design.
